US0D1108897S

(12) **United States Design Patent** (10) **Patent No.:** **US D1,108,897 S**
(45) **Date of Patent:** ** Jan. 13, 2026

(54) **FOLDABLE COASTER**

(71) Applicant: **Xi'an Oumo E-commerce Co., Ltd.,**
Shaanxi (CN)

CN 308622305 * 5/2024

(72) Inventor: **Meijuan Yang**, Zhejiang (CN)

(73) Assignee: **Xi'an Oumo E-commerce Co., Ltd.,**
Xi'an (CN)

(**) Term: **15 Years**

(21) Appl. No.: **29/942,054**

(22) Filed: **May 13, 2024**

(51) LOC (15) Cl. 07-09

(52) U.S. Cl.

USPC **D7/624.1**
